DISPENSER

Hyman B. Grace, London, Ontario, Canada

Application January 16, 1943, Serial No. 472,627

1 Claim. (Cl. 222—320)

This invention relates to new and useful improvements in dispensers and more particularly to a dispenser tube of the non-collapsible type.

The principal object of the present invention is to provide a dispenser tube which can be manufactured from non-critical types of materials during war times and which in use will be just as practical and even more convenient to use than the conventional collapsible tubes at present marketed.

Other objects and advantages of the invention will become apparent to the reader of the following description.

In the drawing:

Figure 1 is a side elevational view of the dispenser with the upper and lower portions thereof broken away.

Figure 2 is a section on the line 2—2 of Figure 1.

Referring to the drawing wherein like numerals designate like parts, it can be seen that numeral 5 denotes a tubular shell having its lower portion threaded to accommodate the internally threaded side wall of a bottom 6 which at its central portion has a raised bearing member 7.

The upper portion of the shell 5 is shouldered as at 8 and at its central portion has a thickened riser 9 exteriorly threaded to accommodate an internally threaded cap 10.

The exteriorly threaded riser 9 has a central opening through which is disposed a shaft 11, the shaft 11 extending downwardly to the bottom 6 where it is formed with a socket to receive the bearing member 7. The upper portion of the shaft 11 just above the riser 9 is provided with a rotor 12 to facilitate rotation of the shaft 11 and the shaft has a small extension 13 rising above the rotor 12 and which is adapted to be abutted by the cap 10 when screwed down tightly 40

The shell 5 has a partition 14 extending inwardly therefrom in a radial direction through-

out the entire height of the shell 5 and the inner edge of this partition 14 barely wipes the periphery of the shaft 11.

The shaft 11 carries a wing 15 which projects outwardly from the shaft 11 in a radial direction and barely wipes the interior side of the shell 5.

A duct 16 extends from the periphery of the shaft 11 just below the shoulder 8 inwardly and then upwardly to open through the upper end 10 of the extension 13.

When the shell 5 is full of material such as toothpaste, shaving cream, etc., the wing member 15 is against or in very close proximity with the partition 14. In order to dispense the contents of the tube 5, the shaft 11 is rotated in the direction of the arrows in Figure 2 with the result, that the material 17 is compressed and forced outwardly through the duct 16 for use.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

A dispensing container comprising a rigid tube having a reduced discharge neck at one end, a rotatable shaft extending into said tube through said neck and having an outer end projecting out of the neck, a radial partition in said tube extending from end to end thereof, a radial wing member on said shaft also extending from end to end of the tube, a right angled discharge duct 30 extending inwardly from the outer end of the shaft and opening into the tube at the neck end thereof, a rotor on the outer end of the shaft for manipulation to rotate the same and seating on said neck to seal the neck around the shaft, and a cap threaded onto said neck against the outer end of the shaft to cover said rotor and close the outer end of the duct.

HYMAN B. GRACE.
